UNITED STATES PATENT OFFICE.

MAURICE M. PHILLIPS, OF PITTSBURGH, PENNSYLVANIA.

WIRELESS RECEIVING CIRCUIT.

Application filed March 20, 1926. Serial No. 96,186.

REISSUED

This invention relates to improvements in wireless receiving circuits and more particularly to improvements in circuits employing the heterodyne method of reception.

5 One object of this invention is to so couple a directional bridged collector circuit with a bridged oscillating detector circuit that the two circuits will function so that a receiver employing the same will cover the entire 10 broadcast range from 545,000 cycles to 1,500,000 cycles, will require but two main variable tuning condensers and will not re-radiate.

This and other objects which will appear 15 to those skilled in this art are attained by means of the circuit arrangement which is diagrammatically illustrated in the single sheet of drawings accompanying and forming part of this application.

20 In a general way the circuit system includes two bridged circuits and means for coupling these bridged circuits together. One of the bridged circuits includes a directional loop, a three-element vacuum tube, a 25 variable capacity for tuning the circuit to carrier frequency and a variable capacity for balancing or neutralizing the inherent grid plate capacity of the vacuum tube and the wiring associated therewith. The other circuit which includes a three-element vacuum tube serving as an oscillating detector also 30 includes a variable capacity for determining the frequency of the locally generated oscillating current used for heterodyning.

35 The bridged circuit which operates as the collector circuit is balanced or neutralized in a manner similar to the method disclosed in Hazeltine Patent No. 1,450,080, of March 27, 1923, while the other bridged circuit embodies the principle disclosed in Pressley 40 Patent No. 1,560,854, of Nov. 10, 1926.

The coupling device between these bridged circuits which serves to transfer the collected signals from one circuit to the other, 45 consists of two aperiodic inductances of suitable value, magnetically coupled together. The output circuit of the bridged collector is conductively coupled to one of these aperiodic inductances, while the input circuit of the 50 bridged oscillating detector is conductively coupled to the other aperiodic inductance.

These aperiodic inductances preferably take the form of an iron core radio frequency transformer.

55 For the purpose of completely disclosing

my invention and in order to facilitate its practical application by those skilled in the art, I give below a detailed description of a part of a circuit system embodying this invention and which may be utilized in a receiver in connection with intermediate frequency and audio frequency amplifiers of any standard form.

Referring to the drawings, more particularly by reference numerals and letters, the 60 loop L which will preferably be mounted so as to be capable of being rotated to different positions is tapped at its exact center and is connected up by means of leads 2 and 2^a to the center arm 3 of a variable resistance T 65 which is preferably in the form of a potentiometer. This resistance is connected across a battery or other current supply A and serves as a throttling device.

The loop L forms two inductive arms of a 70 bridge and the inner ends (junction point) of these inductive arms are connected to lead 2. The other end 4 of one of the inductive arms is connected to the grid 5 of a vacuum tube 6, while the outer end 7 of the other 80 inductive arm of the bridge L is connected to plate 8 of the tube 6 through a variable capacity 9. Variable capacity 9 must be of such value as to be capable of equaling or 85 balancing the inherent capacity existing between the grid 5 and plate 8 (and the connected wiring) of vacuum tube 6.

10 represents a variable capacity connected 90 across loop L and of suitable value to tune loop L to the frequency desired.

The variable resistance T which I term the throttle is connected across the filament battery and conductively couples the bridged collector circuit to the bridged oscillating detector circuit through inductance 12.

The bridged collector circuit is most sensitive when its grid circuit is negatively biased and negative biasing is accomplished by swinging the center arm 3 of variable resistance T toward the negative potential of the 100 A battery. In balancing the bridged collector circuit it is highly desirable to swing center arm 3 to its full negative position.

Upon receiving a strong signal from a 105 nearby transmitter the tendency of the oscillating detector circuit to become blocked can be corrected and as I term it, throttled out, by swinging arm 3 of the variable resistance T toward the positive potential of the A battery. This blocking tendency be-

comes greater as the frequency of the received signal increases and less as the frequency decreases.

Plate 8 of tube 6 is connected to one end 5 of an inductance 11, the other end of the inductance being connected to the positive side of a battery B which is utilized to supply current to plate 8.

Inductance 11 is preferably the primary 10 winding of an iron core aperiodic radio frequency coupling transformer so designed as to be suitable for present day broadcasting reception. 12 represents the secondary winding of said coupling transformer and is conductively coupled to the junction point 13 15 of inductances 14 and 15, while the open end 16 of inductance 12 is connected to movable arm 3 of throttle T.

14 and 15 are preferably of toroidal form 20 and are preferably formed by tapping the secondary of a toroidal coil of suitable inductance at its exact center, thus forming two equal inductive arms. The outer end 25 16 of inductive arm 14 is connected to the grid 17 of a three element vacuum tube 18 through a suitable resistance 19 and capacity 20 (preferably 100,000 ohms and .00025 M. F. D. respectively). Outer end 16 of inductive arm 14 is also connected through a fixed 30 capacity 21 to the negative side of the filament 22 of vacuum tube 18.

The outer end 23 of inductive arm 15 is 35 connected to the negative side of filament 22 through a suitably valued variable capacity 24.

The value of fixed capacity 21 is preferably .00008 M. F. D. and the value of variable capacity 24 is preferably .000045 M. F. D. A variable capacity 25 is connected 40 across inductive arms 14 and 15 and functions to produce the desired frequency of the locally generated oscillations. The capacity of 25 is such as to tune the inductive arms 14 and 15.

45 Inductive arms 14 and 15 and the capacity arms (in one instance including the fixed capacity 21 and in the other, variable capac-

ity 24) form the two inductive and two capacity arms of a bridge.

The filaments 22 and 25 of vacuum tubes 50 18 and 6, respectively, are connected across battery A through a variable resistance 26.

Plate 27 of vacuum tube 18 is connected to one end 28 of an aperiodic coil 29 within the field of inductive arms 14 and 15. The 55 other end 30 of coil 29 is connected to one end of an inductance 31 which forms the output circuit of the second bridge. The other end of inductance 31 is connected to the positive side of battery B. Inductance 32 forms the input circuit of an intermediate amplifier and second detector commonly used to amplify the output of a heterodyne circuit. A by-pass condenser 32 may be utilized as a plate to ground filter. 65

Having thus described my invention what I claim as new and desire to secure by Letters Patent is:

1. A circuit system comprising a bridged collector circuit which includes two inductive arms a three element vacuum tube and a capacity for balancing the inherent grid plate capacity of said tube, a second bridged circuit which includes two inductive and two capacity arms and a three element vacuum tube and two inductances magnetically coupled together and conductively coupled to said circuits. 70

2. A circuit system comprising a directional bridged collector circuit, which includes a directional loop, a three element vacuum tube and a variable capacity for balancing the inherent grid plate capacity of said tube, a second bridged circuit which includes two inductive and two capacity arms 80 and a three element vacuum tube which functions as an oscillating detector and two inductances magnetically coupled together and conductively coupled to said circuits. 85

In testimony whereof, I have hereunto 90 subscribed my name this 18th day of March, 1926.

MAURICE M. PHILLIPS.
